UNITED STATES PATENT OFFICE.

JOHN G. LANNING, OF DETROIT, MICHIGAN, ASSIGNOR TO DETROIT LUBRICATOR COMPANY, OF DETROIT, MICHIGAN, A CORPORATION OF MICHIGAN.

CARBURETOR.

Application filed July 30, 1920. Serial No. 400,087.

The invention relates to carburetors of that type in which the liquid fuel nozzle is in the center of the automatic air valve, being operated by an aspirating passage through said valve and being regulated by a control pin, whereby as the air valve opens the orifice controlled by the control pin is increased in area. It is the object of such constructions to retard the opening of the valve for auxiliary air until the inertia of the liquid fuel has been overcome and to then progressively increase the area of feed opening to the fuel column as the air valve moves towards open position. The retarding of the movement of the valve is either through its own inertia or through additional retarding means, such as a dashpot, and the resistance is adjusted to obtain as far as possible a constant proportion of fuel and air. It has, however, been found difficult to obtain any adjustment which will insure proper acceleration of the liquid without such retarding of the movement of the air valve as to slow its response to the throttle.

It is the object of the present invention to obtain a more instantaneous acceleration of the fuel and with less retardation of the opening of the air valve. It is a further object to delay the re-establishment of normal relation of the fuel to the air current to compensate for the inertia of the moving parts, or in other words, to synchronize the operation of the nozzle with the acceleration of the motor. This I accomplish by means controlling the passage of the fuel, which responds practically instantaneously to an increase in vacuum upon the fuel column, and increases the amount of fuel passing through the control orifice. More specifically, I have accomplished the desired result by the use of an accelerating plunger of small mass and having but a slight element of inertia, said plunger controlling the amount of fuel passing through the orifice and being exposed to the high vacuum above the air valve.

In the drawings:

Figure 1 is a vertical central section through a carburetor embodying my invention;

Figure 2 is an enlarged vertical sectional view of the valve mechanism and aspirating means and showing a slightly modified construction;

Figure 3 is a cross-section on line 3—3 of 55 Figure 1.

A is a casing containing the air inlet passage B, mixing chamber C, outlet D, and controlling throttle E. F is the air valve which engages an annular seat G between 60 the inlet B and mixing chamber C. H is the stem of the valve, which is guided in a bearing I and which at its lower end is provided with a piston J operating in a cylinder K to form a dashpot. Centrally within this stem is the fuel passage L. There is also provided through the valve the aspirating passage N for causing the discharge of the fuel.

With the construction as thus far described and as heretofore constructed, when the throttle is opened, the increased vacuum in the mixing chamber operating upon the aspirating passage and liquid fuel nozzle will cause an acceleration in the movement of the fuel column, while the inertia of the air valve together with the resistance of the dashpot, will delay the opening movement of the valve. It is necessary, however, that the fuel should be accelerated, while the entrance orifice thereto is restricted, for increase in the size of this orifice does not occur until after the air valve begins to move. With my improved construction I have provided means for temporarily increasing the area of opening to the fuel column, so as to decrease the resistance to the acceleration thereof. This, as shown, consists in a tubular member O surrounding a control pin M and slidably arranged within the hollow stem H. The member O is yieldably held in normal position by a spring P arranged between its upper end and a shoulder within the stem, while the lower end engages a suitable stop such as Q. In the modification illustrated in Figure 2 the lower end of the sleeve rests upon an apertured plate Y inserted in the piston J. With this construction the area of the opening orifice into the fuel column is determined by the relative positions of the member O and the control pin M and as the member O is carried by the valve stem H, its position is changed with the movement of the valve, so that it performs the same general function as constructions of the type heretofore used.

When, however, the throttle is suddenly opened and a high vacuum is placed upon the fuel nozzle, the increased differential pressure on the

lower end of the member O will move said member upward relative to the hollow stem H and control pin M, which will increase the area of the entrance orifice. This will 5 facilitate the acceleration of the fuel and as soon as the pressures are again equalized, the spring P will return the member O to its normal position determined by the stop Q.

- 10 The discharge and primary atomization of the liquid fuel is largely effected by the ejector effect of the aspirating air passage through the valve. To increase this effect I have formed this aspirating passage as a 15 modified venturi and in place of discharging the liquid vertically, it is discharged through a series of lateral ports adjacent to the throat of the venturi in the plane of greatest suction.
- 20 In detail, the valve F has a cap member R, which is fashioned with a Venturi passage therethrough which at its lower end is fed with air through ports S in the body of the valve. T is a nozzle fitting arranged at 25 the upper end of the stem H and extending into the throat of the Venturi passage, the external surface of said fitting being fashioned to conform to a portion of the Venturi passage. A hollow plug X is removably positioned within the lower end of the nozzle and extends below the same in engagement with the upper end of the spring P. U is a cap for closing the top of the nozzle T, and V are a series of small ports, 30 communicating with the interior of the nozzle and discharging into the throat of the venturi. This construction produces a better atomization and commingling of the liquid fuel with the air and also a better 35 ejector effect for starting the discharge of fuel from the nozzle.

The valve F is retarded in its movement by a dashpot formed by the piston J in the cylinder K. It is desirable that the resistance should be greatest during the initial 45 opening of the valve, which is accomplished by a close fit of the piston to the cylinder in position for initial opening and an increased clearance as the piston moves towards open position of the valve. Thus, as 50 shown, a tapering channel W is formed in one side of the cylinder which, after the piston is lifted a certain distance, will progressively increase the opening through 55 which the liquid in the dashpot can pass from one side of the piston to the other.

The construction just described I do not

broadly claim as my invention, but I have found that in combination with the features above, the carburetor as a whole is much more sensitive and flexible in its operation. Means other than the specific construction shown can be employed for the same purpose.

In operation, whenever the throttle is suddenly opened, a high vacuum will be communicated to the mixing chamber C and through the ports V to the interior of the nozzle. This will cause an increased differential pressure on the lower end of the member O, as has been before described, which results in the raising of this member and the increasing of the entrance orifice to the liquid fuel column. The upward movement of the valve F is delayed by its inertia and the resistance of the piston J, so that the high vacuum is maintained long enough to accelerate the fuel, while the initial movement of the valve is greatly retarded. As soon, however, as the piston has moved forward a short distance, the increased clearance afforded by the channel W will decrease the resistance and permit quick acceleration in the movement of the valve.

The effect of the construction is not only to produce better acceleration, but also to accomplish proper deceleration. Thus when the throttle is quickly closed, the air valve will rapidly drop towards its seat and the proper mixture will be obtained during deceleration.

What I claim as my invention is:

In a carburetor, the combination with an automatic air valve having a liquid fuel passage through the stem thereof, of a control pin arranged within said stem to regulate said passage, an independently movable sleeve surrounding said pin and within said stem, said movable sleeve cooperating with said control pin to form an inlet orifice for said fuel passage and being exposed to pressure below said orifice, said member being of small mass compared to the mass of said automatic air valve, and movable by differential pressure on the opposite sides of said inlet orifice to vary the opening of said orifice independent and in advance of the movement of said valve and yieldable resilient means between said sleeve and said valve for permitting said independent movement and gradually restoring said sleeve to normal position.

In testimony whereof I affix my signature.

JOHN G. LANNING.
